A. J. Faxon,
Screw Propeller.

No. 16,091.

Patented Nov. 18, 1856.

UNITED STATES PATENT OFFICE.

A. JOUAN, OF SAN FRANCISCO, CALIFORNIA.

PROPELLER-SHAFT.

Specification of Letters Patent No. 16,091, dated November 18, 1856.

To all whom it may concern:

Be it known that I, AUGUSTUS JOUAN, of the city of San Francisco, in the State of California, have invented a new and useful 5 Improvement in the Construction of Steam Propeller-Shafts, and do hereby declare that the following is a full and exact description thereof, reference being had to the accompanying drawings and to the letters 10 of reference marked thereon.

The nature of my invention consists in providing for steam propellers a shaft which combines several advantages, among which that of the great facility of raising and lowering 15 the propeller and that of not interfering with the proper location of the rudder.

To enable others skilled in the art of constructing and navigating vessels, to make and use my invention, I will proceed to describe 20 my said invention.

This shaft is specially intended for steamer propeller shafts. It can be made of any metal but brass should be preferred. It is composed of three parts (A) (B) (C) 25 united by keys. Its form is conical, about the half of its length circular and the balance triangular as shown by (A). The upper end of the shaft hangs vertically from the poop of the vessel and the lower end is 30 connected with a strong metallic stanchion, firmly made to adhere to the stern post, though the main bearer of the weight of the shaft is the cushion on which the shaft principally revolves and which is fixed on the 35 poop, the said stanchion being but an auxiliary instrument for the revolution of the shaft and for bearing its weight and is principally intended to support the shaft when the vessel is inclined. The conductor of the 40 motor after passing through the stern post, connects with the shaft at its base.

For the use of this shaft, the poop of the vessel must be constructed in a way similar as shown in drawing (D).

45 The peculiar form of this shaft is calculated to suit several purposes; the angular part of it is convenient to raise the propeller out, and that is done with an ordinary power; to lower it, the action of its own weight 50 is sufficient, the propeller goes down and settles where it is intended, producing the extraordinary advantage that by a simple arrangement which can easily be contrived, the propeller can be raised or lowered so as 55 to follow the variation of the water draft of

the vessel and be placed to operate in the depth most convenient. To that effect nothing is necessary but a concave angle cut in the central part of the propeller, combining with the convex angle of the shaft; to facilitate the whole operation the angle of the shaft commences at about two feet above the water line of the vessel, when the vessel 60 is in good sailing trim.

From the angular form of the shaft, particularly when it is triangular, among other utilities is resulting that when the vessel is sailing without the aid of steam and the propeller is hoisted up, the shaft can be placed so that one of the angular edges will 65 front the vessel, and in that way, less resistance will be made to headway. With such a combination of shaft and propeller, the propeller can not become loose, as happens frequently with other arrangements, 70 causing to vessels the necessity of touching at a port for repair. The location of the rudder on the stern post will be appreciated by navigators.

Very proper remarks have been made in 75 regard to the difficulty of steering, consequent to the propeller being placed forward of the rudder, causing the water to arrive on the rudder after having lost its steering power.

80 I am of opinion that this shaft requires a propeller placed obliquely and consequently I have applied such a one to my shaft model, not that I believe its form exclusively to be the most advantageous to be 85 used, but to express an impression that I have. It stands about ten degrees obliquely with the shaft, its form when revolving represents an oval circle; the blades are of steel, tempered for most elasticity, those are only 90 painted but should be galvanized, painted 95 and covered with a coat of gutta percha.

85 What I claim as my invention and desire to secure by Letters Patent is—

A propeller shaft, which in its construction is, circular, conical and angular, with these three conditions combined or otherwise, and to be applied vertically as herein described and shown and for the purpose above set forth.

A. JOUAN.
